(57) **CLAIM**

I claim the ornamental design for a magazine holder, as shown and described.

DESCRIPTION

FIG. 1 is a right side view of a magazine holder in a closed position showing my new design;

FIG. 2 is a right side view of the magazine holder in an open position;

FIG. 3 is a rear view of the magazine holder of FIG. 2;

FIG. 4 is a top view of the magazine holder in a closed position;

FIG. 5 is a top view of the magazine holder in an open position; and,

FIG. 6 is a top view of a magazine holder in an open position, showing a magazine inserted therein for illustrative purposes.

Throughout the drawings, the short thin dashed lines represent either footwear and a magazine as an illustrative environment of the Magazine Holder of my new design, and the thick dashed lines on a flap of the Magazine Holder illustrate stitching that is not claimed.
